Primary Examiner — Mark A Goodwin(74) *Attorney, Agent, or Firm* — Suiter Swantz pc llo(57) **CLAIM**

The ornamental design for a tractor mat, as shown and described.

DESCRIPTION

FIG. 1 is a top perspective view of the tractor mat showing my new design;

FIG. 2 is a bottom perspective view thereof;

FIG. 3 is a top plan view thereof;

FIG. 4 is a bottom plan view thereof;

FIG. 5 is a front elevation thereof;

FIG. 6 is a back elevation thereof;

FIG. 7 is a side elevation thereof;

FIG. 8 is a second side elevation thereof; and,

FIG. 9 is a top perspective view showing the tractor mat installed on a floor of a tractor.

The broken lines shown in the figures represent portions of the tractor mat or a tractor cab environment that form no part of the claimed design.
